CLAIM

The ornamental design of a lap tray, as shown and described.

DESCRIPTION

FIG. 1 is a perspective view looking toward the top of a lap tray, showing my new design;

FIG. 2 is a top plan view of FIG. 1;

FIG. 3 is a left side elevational view of FIG. 1; the right side elevational view being identical to that shown;

FIG. 4 is a bottom plan view of FIG. 1;

FIG. 5 is a right end elevational view of FIG. 1; and,

FIG. 6 is a left end elevational view of FIG. 1.
